ROPE STRUCTURE

Application filed January 26, 1924. Serial No. 688,703.

This invention relates to the construction of rope, particularly of wire rope, of which the wire strands are covered or wrapped with fibrous material. Among the objects of the invention are to provide rope of this character in which the fibrous material, which is wrapped around the wire strands, is impregnated with a preservative and lubricant composed of copper oleate, or the copper or any 10 equivalent salt of any fatty acid of the fatty acid series. The result of wrapping the wire strands of a rope with fibrous material thus treated is to increase the durability of the structure by reason of the lubricating qualities of the oleate; to preserve the fibrous wrapping from the deleterious effects of atmosphere, water, etc. Incidentally the fibrous wrapping of the strands so treated constitutes an easily recognizable and characteristic marker.

In the accompanying drawings, we have illustrated a wire rope embodying our invention. In the drawing,

Figure 1 is an elevation of such a rope; and 25 Figure 2 is a section on the line 2—2 of Figure 1.

Referring to the numerals on the drawing, the wire strands in the rope structure are indicated at 3, while 4 indicates a wrapping 30 of fibrous material which has been impregnated with a preservative lubricant, such as copper oleate or the copper or equivalent salt of any fatty acid of the fatty acid series.

We claim:

55 A composite rope consisting of a core member twisted from a plurality of fibrous strands in one direction and a plurality of wires laid around the core in the opposite direction, each of said wires being incased in 40 a plurality of casing strands spirally wound on the respective wire in the same direction as the core winding, said casing strands being impregnated with a lubricant, said lubricant containing a copper salt.

45 In testimony whereof we affix our signatures.

HAROLD M. WALL.
WALDO REINER.
